SKIMMER-COVER FOR SWIMMING POOLS

George Welborn, 1432 N. Sycamore,
Hollywood, Calif. 90028

Filed Jan. 7, 1971, Ser. No. 104,831

Term of patent 14 years

Int. Cl. D23—01

U.S. Cl. D23—4

FIG. 1.

FIG. 2.

FIG. 3.

FIG. 4.

FIG. 5.

FIG. 1 is a perspective view of a skimmer-cover for swimming pools, showing my new design;

FIG. 2 is a top plan view thereof;

FIG. 3 is a side elevational view thereof;

FIG. 4 is a bottom plan view thereof; and

FIG. 5 is a central vertical cross sectional view thereof.

I claim:

The ornamental design for a skimmer-cover for swimming pools, as shown.
